(57) CLAIM

I claim the ornamental design for a male undergarment, as shown and described.

DESCRIPTION

FIG. 1 is a perspective view of a first embodiment of male undergarment showing my new design;

FIG. 2 is a front view thereof;

FIG. 3 is a left side view thereof, it being understood that a right side view is a mirror image thereof;

FIG. 4 is a top view thereof;

FIG. 5 is a bottom view thereof; and

FIG. 6 is a rear view thereof;

FIG. 7 is a perspective view of a second embodiment of male undergarment showing my new design;

FIG. 8 is a front view thereof;

FIG. 9 is a left side view thereof, it being understood that a right side view is a mirror image thereof;

FIG. 10 is a top view thereof;

FIG. 11 is a bottom view thereof; and,

FIG. 12 is a rear view thereof.

Broken lines indicate unclaimed subject matter and form no part of the claimed design.

1 Claim, 4 Drawing Sheets(56)
